DISPENSING DEVICE FOR CALKING
MATERIAL AND THE LIKE

William A. Sherbondy, Shaker Heights, Ohio

Application December 3, 1947, Serial No. 789,352

11 Claims. (Cl. 222—327)

1

The present invention relates to a dispensing device for calking material and the like and is concerned particularly with means for holding a cartridge containing the material in position for expulsion of the material by the manual operation of a plunger. The dispensing device comprises a handle in which one end of the cartridge may be mounted, and means connected to the handle to engage the far end of the cartridge and hold it in place, the handle carrying also a plunger and the operating mechanism therefor to expel the contents of the cartridge, the cartridge thus itself forming the barrel of what may be called a "calking gun."

The present invention is concerned especially with the means for engaging the far end of the cartridge and particularly with a discharge spout carried by such means and adapted to make a tight connection with the forward end of the cartridge.

In its preferred form my cartridge comprises a paper tube having an internal cap which may form a closure at one end and may act as a head for a plunger in extruding material from the other end, the latter end having a cap with a central opening through which the extrusion takes place. The device which carries the cartridge has a plate to engage its front end and a spout adjustably carried by the plate and adapted to be caused to abut the front end of the cartridge to make a tight connection therewith so that the material may be extruded through the spout without leakage.

My invention comprising the means by which I accomplish the above result is illustrated in the drawing hereof and is hereinafter more fully described.

In the drawings, Fig. 1 is a side elevation partly in section and partly broken away, of the dispensing apparatus the full-line showing of the bail and front plate indicating the idle position, and the broken lines showing these parts as they are being brought into place to engage the cartridge, which is also indicated in broken lines; Fig. 2 is a rear elevation of the dispensing apparatus; Fig. 3 is an enlarged horizontal fragmentary section through the forward portion of the handle, indicating part of the cartridge in position; Fig. 4 is a side elevation of the complete apparatus with the cartridge in place, the plunger rod being intermediately broken out and different positions thereof indicated in broken lines; Fig. 5 is a plan of the complete apparatus with the cartridge in place; Fig. 6 is an enlarged vertical section through the front retainer plate

2

and the adjacent portion of the cartridge, showing the parts in position immediately after the cartridge has been put in place; Fig. 7 is a similar section indicating the spout screwed in against the forward end of the cartridge, and Fig. 8 is an end elevation of the front retainer plate carrying the spout.

As shown in Figs. 1, 4 and 5, 10 indicates the body of the cartridge which is a paper tube similar to a mailing tube preferably spirally wound. This cartridge carries an internal cap 11, Fig. 2, which when the cartridge is loaded lies adjacent one end thereof and forms a closure therefor. It is pushed into the cartridge by the gun mechanism to expel the contents through a closure cap 12 at the forward end. The closure cap 12, as shown in Figs. 6 and 7 comprises a resilient disc-like member having an annular portion 13 to engage the interior of the barrel 10 with an outwardly extending flange 14 to abut the end of such barrel, with a final outside flange 15 clamping against the exterior of the barrel. This closure plate is provided with a central opening 16 through which the discharge takes place, the cap being annularly flanged outwardly at 17 about this opening.

When the cartridge is used in the shipping container the discharge opening 16 is closed by a thin frangible seal (not shown) extending across the interior of the opening. The internal cap 11 at this time is at the other end and forms an effective closure for that end of the cartridge.

My skeleton gun in which such a cartridge as described may be mounted comprises a suitable handle 20 in the form of a hand grip rigidly carrying a forwardly facing cylindrical cup 21 in which the rear end of the cartridge may be mounted.

To engage and hold the forward end of the cartridge I provide a bail 30 which is pivoted at 31 to the handle body and at its far end carries a plate 32 adapted to engage the front end of the cartridge and hold it in position with its rear end in the cup 21. The plate 32 has a central outwardly extending flange 33 which is internally threaded. In this thread is mounted the spout 35 which carries external threads meshing with the internal threads of the plate. The spout has a slight annular flange 36 at its inner end limiting its outward movement when such flange engages the plate. The forward face of the flange 36 is conical and when the spout is completely withdrawn seats in a conical recess in the front plate 32 to bring the extreme inner end of the spout flush with the inner face of

the plate, as shown in Fig. 6. This enables the plate to be slid readily across the end of the cartridge without obstruction.

The forward flange 17 on the cartridge cap 12 is of such size that it may readily but snugly occupy the interior of the spout. When the cartridge is in place the spout is screwed inward manually until its end abuts the cartridge cap 12, the spout embracing the flange 17, as shown in Fig. 7. This makes a tight connection between 10 the spout and the cartridge.

The front closure plate 12 is resilient, enabling the spout to make a tight connection therewith, whether the spout occupies such a position as shown in Fig. 7, with its inclined end 31 facing downwardly or in the diametrically opposite position with the incline facing upwardly. Accordingly, the spout may be turned to present the incline in any direction desired and still maintain a tight connection with the cartridge cap. The flange 36 and a bulge at the other end of the spout thread permanently retains the spout in the plate 32.

The front plate 32 is provided with a rearwardly extending lip 38 at its lowermost portion adapted to extend beneath the cartridge while at its upper portion it has a forwardly extending lip 39 adapted to provide a finger grip for conveniently holding the plate while the cartridge is being put in place.

The bail 30 is shown as held at its intermediate portion on the front of the plate 32 by ears 40 (Fig. 8) partially severed from the plate and overhanging the bail. The bail is intermediately looped downwardly as at 41 to clear the spout. This downward loop on the bail operates as a stop to engage the spout and limit its downward swing relative to the bail, as shown in full lines in Fig. 1.

The rear ends of the bail are shown as pivoted to the handle by having inturned portions 43 (Fig. 2) which lie between rearwardly bowed portion 44 of the side flanges 22 of the sheet metal hand grip 20 and the cup 21. These flanges are preferably riveted to the cup by integral partially severed lugs 45 (Figs. 2 and 3).

The extreme ends of the bail are turned at an angle to extend upwardly, as shown at 46, to hold the bail in position in its pivotal anchorage. These upturned ends 46 also serve to limit the possible downward swing of the bail as shown in Fig. 1. Accordingly when the hand grip 20 is held in the user's hand the bail and forward plate and spout naturally drop by gravity in some such position, as shown in full lines in Fig. 1, leaving the space in front of the handle cup 21 entirely unobstructed for the mounting of the cartridge.

In mounting the cartridge in the gun the plunger plate is withdrawn into the cup, the cartridge placed in the cup, the front plate 32 swung upwardly across the front end of the cartridge until the bottom lip 38 abuts the undermost portion of the cartridge. This movement swings the plate into position at right angles to the cartridge axis and locates the cartridge accurately with reference to the discharge spout and then the spout is manually screwed in until it abuts the front end of the cartridge and makes a tight connection therewith.

Any suitable mechanism may be provided on the handle for operating the plunger to force the contents out of the cartridge. As shown, the hand grip 20 carries a longitudinal rod 23 having a plunger plate 24 at its forward end and has

an operating lever 25 for moving a spring-pressed pawl 26 (Fig. 1) to feed the rod forwardly. A suitable detent pawl 27 retains the gain made in such feeding. As shown the plunger rod has teeth 28 along one edge. When the rod is turned to present these teeth upwardly (as indicated by broken lines 29 in Figs. 1 and 4) the rod may be freely withdrawn toward the right. To feed the material the rod is turned with its bent end 29 extending downwardly which places the teeth where the pawls act on them, so that the hand lever 25 may forwardly feed the rod into the cartridge.

It will be seen that my manually operated apparatus is an extremely simple and relatively inexpensive construction; that the cartridge, with a discharge opening closed by a frangible seal, may be readily mounted therein and when so mounted a complete calking gun is provided. 15 Such gun has conveniently operable manual mechanism for extruding the material through the discharge spout, enabling use of the apparatus in the usual manner of a calking gun. The cartridge may remain in the apparatus as 20 part of the complete gun until the material has been entirely used. Thereafter, merely rotating the spout in the direction to screw it out and withdrawing of the plunger rod will free the used cartridge and enable the installation of a fresh 25 one.

I claim:

1. The combination of a handle having means for seating the rear end of a cartridge, a member pivotally carried by the handle and adapted to swing into and out of alignment with the forward end of such cartridge, a spout screw-threaded in said member and adapted to be moved by said screw threads when the spout is turned to abut the forward end of the cartridge, and means carried by the handle for expelling the contents of the cartridge through the spout.

2. The combination of a handle having a seat for the rear end of a cartridge, a bail pivotally connected to the handle, a spout carried by the forward end of the bail, and means on said forward end of the bail and said spout for moving said spout longitudinally relative to said bail to abut the forward end of the cartridge.

3. The combination of a handle having means for seating the rear end of a cartridge, a bail pivotally connected to the handle, a front plate pivotally connected to the bail, said plate having a bottom lip to engage the under edge of the cartridge when in position, a spout screw-threaded in the front plate, and means carried by the handle for expelling the contents of the cartridge.

4. In a dispensing device for calking material and the like, the combination of a handle, a front plate, a spout screw-threaded in the front plate, a bail pivoted to the handle having its intermediate portion extending across the front of the plate and having a loop extending freely about the spout, and means pivoting the bail at either side of the loop to the front plate.

5. The combination of a handle having a seat carried thereby to receive one end of a cartridge, a bail pivoted to the handle, a front plate pivoted to the intermediate portion of the bail, a spout screw-threaded in the front plate and adapted to engage the front of a cartridge having the rear end thereof in the handle seat, and means carried by the handle for expelling the contents of the cartridge through the spout.

6. The combination of a handle adapted to form a seat for the rear end of the cartridge, a

front plate adapted to abut the front of the cartridge, a pair of rods adapted to lie on opposite sides of the cartridge and pivoted at their rear ends to the handle and at their front ends to the plate, and means for limiting the downward movement of the rods with reference to the handle.

7. The combination of a handle adapted to form a seat for the rear end of the cartridge, a front plate adapted to engage the forward end of the cartridge, means connecting the front plate with the handle, a spout screw-threaded in the front plate and having an outward flange at its inner end adapted to seat in an annular recess in the inner side of the front plate whereby the rear end of the spout may be flush with the inner face of the plate, said spout by reason of its screw-thread being adapted to be moved inwardly to abut the forward end of the cartridge.

8. The combination of a handle having a forwardly facing cup adapted to form a seat for the rear end of a cartridge, a plate adapted to engage the front end of the cartridge, a spout threaded in the front plate and adapted when in one position to have its inner end flush with the inner face of the plate and in another position to abut the front end of a cartridge seated in the cup, said front plate being connected with the handle by means of a pair of rods on opposite sides of the cartridge pivotally connected at their rear ends to the handle and at their forward ends to the plate.

9. The combination of a cartridge having a cap at its forward end with a discharge opening surrounded by a forwardly projecting annular flange, a handle having a seat for the rear end of the cartridge, a plate pivotally connected to the handle and adapted to engage the front end of the cartridge, and a spout screw-threaded in the plate and adapted to be moved rearwardly by rotation relative to said plate to surround the annular flange on the cartridge.

10. The combination of a cartridge having its forward end providing with a resilient closing, a cap with a central discharge opening, a handle having means for seating the rear end of the cartridge, a plate pivotally connected to the handle and adapted to engage the forward end of

the cartridge, a spout screw-threaded in the plate and adapted to make a tight connection with said resilient cap in various angular positions of the spout, and means carried by the handle for expelling the contents of the cartridge.

11. A dispensing device for calking material and the like comprising a handle having a forwardly extending cup, said handle being formed with a pair of outward flanges riveted to the rear face of the cup, a plunger rod carried by the handle, a lever pivoted to the handle, a pawl operated by the lever to feed the plunger rod forwardly and means carried by the handle to retain the gain made by such forward feeding, a plate adapted to engage the front end of a cartridge mounted in the cup, a pair of rods adapted to stand respectively on opposite sides of the cartridge and pivoted at their front ends to the plate, the rear ends of such rods being turned inwardly and pivoted to the handle by reason of having the inturned ends extending between the handle-flanges and said cup, the extreme rear ends of said rods being adapted to abut the rear face of the handle flanges to limit the downward movement of the forward end of the rods, said plate having a rearwardly extending bottom lip to engage the bottom edge of the cartridge and limit the upward movement of the plate and a spout screw-threaded in the plate and adapted to abut a resilient cap at the forward end of a cartridge, said cap having a discharge opening surrounded by a forwardly extending annular flange adapted to enter said spout when the latter is threaded in said plate inwardly against the cap, said spout when screwed outwardly having its inner end substantially flush with the inner face of said plate.
